(57) CLAIM

I claim, the ornamental design for a car, toy replica and/or other replicas, as shown and described.

DESCRIPTION

FIG. 1 is a front view of a car, toy replica and/or other replicas, showing my new design;

FIG. 2 is a side view thereof taken from the left of FIG. 1;

FIG. 3 is a side view thereof taken from the right of FIG. 1;

FIG. 4 is a rear view thereof;

FIG. 5 is a top view thereof; and,

FIG. 6 is a front and side perspective view thereof.
